UNITED STATES PATENT OFFICE.

PATRICK LARKIN, OF WASECA, MINNESOTA.

TRACK-JACK.

SPECIFICATION forming part of Letters Patent No. 373,744, dated November 22, 1887.

Application filed January 20, 1887. Serial No. 234,966. (No model.)

To all whom it may concern:

Be it known that I, PATRICK LARKIN, a citizen of the United States, residing at Waseca, in the county of Waseca and State of Minnesota, have invented a new and useful Track-Jack, of which the following is a specification.

This invention relates to track-raisers for railways, the object of the invention being to enable the lever or claw-bar to be shifted to a higher fulcrum without changing the position of the base and standards comprising the fulcrum-block.

To this end the invention consists in novel features of construction and combinations, to be hereinafter fully described and claimed.

In the accompanying drawings, Figure 1 is a side elevation of the device in position for raising one side of a track. Fig. 2 is a bottom plan view of the lever. Fig. 3 is a rear elevation of the fulcrum-block. Fig. 4 is a front elevation of the same.

The fulcrum-block consists of a rigid base or platform, *a*, of a width to fit between cross-ties of a track, to the upper side of which, near the front end, are bolted the foot-pieces *b'* of the standards *b*. These standards are arranged parallel with each other and at right angles with the base or platform *a*, their rear edges being provided with downwardly-inclined notches *b*², to receive the fulcrum stud or pin *d'* of the lever or claw-bar *d*. To the rear outer edges of the base *a* are bolted the lower ends of brace-rods *c*, said brace-rods being inclined forwardly and inwardly, and connected at their upper ends to the upper ends of the standards *b* by a stay-bolt, *f*, which also serves to brace the upper ends of the standards at the proper distance apart and to secure a handle or bail, *e*, as shown.

The lever *d* may be a claw-bar of ordinary construction, except that it is provided at a little distance from its lower end with a transverse fulcrum-stud, *d'*, the ends of which project at either side of the lever and are adapted

to engage the inclined notches *b*² in the rear vertical edges of the standards *b*.

In operation the end of the base or platform *a*, extending forward of the standards, is shoved beneath a rail-chair between the cross-ties, with the front edge of the standards in juxtaposition with the foot of the rail. The lower end of the lever *d* is now to be inserted beneath the rail; or, in case the latter rests upon the ground, beneath the head of the rail, and the stud *d'* dropped into a pair of notches, *b*², 55 abreast the point of contact between lever and rail. The free end of the lever is now depressed to raise the rail and cross-ties for tamping or other purposes, and this operation may be repeated until the rail and ties are 60 raised the required distance by simply moving the fulcrum-stud of the lever to a higher pair of notches, and without moving the base and standards nearer to or farther from the rail, as the series of notches are in a vertical 65 plane.

Having thus described my invention, what I claim, and desire to secure by Letters Patent, is—

In a track-raising device for railways, the combination, substantially as described, of the fulcrum-block comprising a flat base, parallel standards rising vertically from the base and having their rear notched edges at right angles thereto, the brace-rods and handle secured 70 to the upper ends of the standards by a stay-bolt, and the lever provided at a distance from its lower end with a fixed fulcrum-stud projecting on either side of the lever and adapted 75 to engage the notches in the rear edges of the standards, whereby the fulcrum-stud of the lever may be shifted to a higher pair of notches 80 without changing the position of the fulcrum-block.

PATRICK LARKIN.
